UNITED STATES PATENT OFFICE

101,526

DESIGN FOR A TEXTILE FABRIC OR SIMILAR ARTICLE OF MANUFACTURE

John F. Gaul, Jr., Clifton, N. J., assignor to Bot-
any Worsted Mills, Passaic, N. J., a corporation
of New Jersey

Application June 19, 1936, Serial No. 63,396

Term of patent 14 years

To whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The repeat unit is indicated between the broken lines shown in the drawing.

The characteristic feature of the present design resides in a plain base fabric which is loosely

woven, resulting in a rough or crêpe-like appearance and series of vertically disposed lines or ribs formed of a multiplicity of thickened threads, such ribs being constituted of groups of three across the face of the fabric, and nubs formed of threads of greater thickness than those forming the ribs, said nubs being disposed in series vertically of the fabric substantially in line with said ribs as shown.

I claim:

The ornamental design for a textile fabric or similar article of manufacture substantially as shown and described.

JOHN F. GAUL, JR.
